UNITED STATES PATENT OFFICE.

WILLIAM REDFORD MULOCK, OF WINNIPEG, MANITOBA, CANADA.

PLATEN FOR TYPE-WRITING MACHINES.

1,186,492.

Specification of Letters Patent.

Patented June 6, 1916.

Application filed November 3, 1915. Serial No. 59,439.

To all whom it may concern:

Be it known that I, WILLIAM REDFORD MULOCK, a subject of the King of Great Britain, residing at Winnipeg, in the Province of Manitoba, Canada, have invented certain new and useful Improvements in Platens for Type-Writing Machines, of which the following is a full, clear, and exact specification.

10 This invention relates to platens for type-writing machines and has for its object to reduce the noise incident to the type striking the platens and at the same time produce clear impressions.

15 In order that clear impressions of the type may be produced upon the paper, it is necessary for the platens to be provided with a hard surface, while to lessen the noise, the surface must be capable of yielding under 20 the impact of the strokes. To accomplish both results, I provide the working surface of the platens with metal coverings below which are arranged elastic cushioning material. The metal casing is made relatively 25 thin and divided into small parts in order to obtain the maximum resiliency without impairing the clearness of the impressions.

30 The invention will be first hereinafter described in connection with the accompanying drawings, which constitute a part of this specification, and then more specifically defined in the claims at the end of the description.

35 In the accompanying drawings, wherein similar reference characters are used to designate corresponding parts throughout the several views: Figure 1 is a side elevation of one end of a cylinder platen constructed substantially in accordance with 40 this invention. Fig. 2 is a transverse section taken on the line II—II of Fig. 1. Fig. 3 is an enlarged fragmentary section taken on the line III—III of Fig. 1. Fig. 4 is a side elevation of one end of a cylinder platen 45 having another form of metal casing composed of longitudinal strips or wires. Fig. 5 is a side elevation of one end of a cylinder platen having an outside casing composed of angularly arranged strips or wires. 50 Fig. 6 is an enlarged section taken on the line VI—VI of Fig. 4. Fig. 7 is an enlarged fragmentary section taken on the line VII—VII of Fig. 4. Fig. 8 is an enlarged cross section through a single strand of bare 55 wire of which the casing for the platen may be made, showing the roughened surface of

the wire to prevent the paper from slipping and Fig. 9 is a similar view of a modified form of wire having a covering with a roughened surface.

60 Referring first to Figs. 1, 2 and 3, the cylinder platen 1 is provided with a layer of soft rubber 2 around which is placed the relatively thin metal covering which, as shown in Fig. 1, may consist of a spirally arranged wire 3, closely coiled or otherwise arranged to form a substantially even surface. This coiled wire is of fine gage or very narrow, so that the impact or stroke of the type will be on or against as small a hard surface as possible. The coiled wire 3 may be secured in place by having its extremities turned in and embedded well down within the elastic cushioning layer 2, as indicated at 5, or in any other suitable manner.

65 As illustrated in Figs. 4, 6 and 7, the wire composing the metal casing may be made in strips or wires arranged longitudinally, or said strips or wires may extend angularly across the platen, as at 7 in Fig. 5, the ends 70 of the strips or wires being suitably secured upon the elastic cushioning layer 2. One way of holding these longitudinal strips 6 and angularly arranged strips 7 in place, as illustrated in the 75 drawings, consists in rabbeting the ends of the strips, as at 9, and placing metal bands 8 around the elastic cushioning layer 2 so as to overlap said rabbeted ends of the strips. Of course, any other suitable means 80 for retaining the strips 6 and 7 in proper position upon the elastic cushioning layer 2 may be employed without departing from 85 my invention.

90 The wire or strips composing the metal covering for the platen may be used in a bare state, but the surface thereof is preferably roughened, as indicated at 10 on the wire 3 in Fig. 8, to prevent the paper from slipping, or in other words, to insure the paper moving precisely with the platen and thus maintaining the proper alinement of the typewritten lines on the paper. This roughened surface may be obtained by the use of acid, or in any other suitable manner. 95 If desired, the wire or strips may be covered with a coating or covering having a more or less roughened surface, as suggested at 31 on the wire 30 in Fig. 9, to accomplish the same purpose. I am aware that other modifications may be made in the structures illustrated and described herein without depart- 100 105 110 115

ing from my invention, and I therefore reserve the right to make such changes as fairly fall within the scope of the appended claims.

5 Having thus described my invention, what I claim as new and desire to secure by Letters Patent of the United States is:

1. A noise reducing platen for typewriters, having a layer of an elastic cushioning substance, and a hard outside casing surrounding the elastic cushioning layer and mounted entirely on the same, said casing being composed of small parts adapted to move independently of one another under the impact of the type and by reason of the yielding quality of the elastic cushioning layer.

10 2. A noise reducing platen for typewriters having a layer of an elastic cushioning substance, and an outside casing composed of a relatively thin layer of wire coiled about

said elastic cushioning layer to form a substantially even surface.

3. A noise reducing platen for typewriters having a layer of an elastic cushioning substance, and an outside casing composed of a relatively thin layer of wire coiled about 25 said elastic cushioning layer to form a substantially even surface, the outer surface of said wire being roughened for the purpose specified.

4. A noise reducing platen for typewriters having a layer of an elastic cushioning substance, and an outside casing composed of a relatively thin layer of wire coiled about 30 said elastic cushioning layer to form a substantially even surface, the strands of the wire being arranged close together on the surface of the elastic cushioning layer.

35 In testimony whereof I have signed my name to this specification.

WILLIAM REDFORD MULOCK.
